US00D656980S

(12) **United States Design Patent**
Liao et al.

(10) **Patent No.:** US D656,980 S
(45) **Date of Patent:** ** Apr. 3, 2012

(54) **PROJECTOR**

- (75) Inventors: **Jung-Mao Liao**, Hsin-Chu (TW);
Chi-Chen Chen, Hsin-Chu (TW);
Chia-Tien Chen, Hsin-Chu (TW)
- (73) Assignee: **Optoma Corporation**, New Taipei (TW)
- (**) Term: **14 Years**
- (21) Appl. No.: **29/377,932**
- (22) Filed: **Oct. 28, 2010**
- (51) **LOC (9) Cl.** 16-02
- (52) **U.S. Cl.** D16/235; D14/217; D16/225
- (58) **Field of Classification Search** D16/203,
D16/213, 221, 225, 229, 230–231, 234–235;
D21/514; 353/115, 119, 122; D8/29; D14/434,
D14/435.1, 217; D13/108, 107; 320/114–115;
361/600; 455/556.1, 556.2
